Primary Examiner — Sheryl Lane(74) Attorney, Agent, or Firm — Gottlieb, Rackman & Reisman, P.C.CLAIM

The ornamental design for a vase, as shown and described.

DESCRIPTION

FIG. 1 is a perspective view of the vase showing our new design;

FIG. 2 is an enlarged top plan view thereof;

FIG. 3 is a rear elevational view thereof, a front elevation view being a mirror image thereof;

FIG. 4 is a left side elevational view thereof, a right side elevational view being a mirror image thereof; and,

FIG. 5 is a bottom plan view thereof.

The broken lines represent portions of the vase that form no part of the claimed design.

The vase is shown with symbolic breaks. The appearance of any portion of the vase between the break lines forms no part of the claimed design.
